KEYHOLDER

Lawrence Samuel, 159 Ralston Ave.,
San Francisco, Calif. 94132

Filed Oct. 7, 1968, Ser. No. 13,868

Term of patent 14 years

Int. Cl. D4—99

U.S. Cl. D87—8

FIG. 2

FIG. 1

FIG. 4

FIG. 3

FIG. 6

FIG. 9

FIG. 5

FIG. 8

FIG. 11

FIG. 7

FIG. 10

FIGURE 1 is a front elevation of the keyholder embodying my invention;

FIGURE 2 is a top plan view thereof;

FIGURE 3 is a bottom view;

FIGURE 4 is an end elevation taken from one end, and is substantially the same as the end elevation from the other end and the end elevation of the FIGURE 5 embodiment described below;

FIGURE 5 is a side elevation of a modified form of the FIGURE 1 embodiment of my invention;

FIGURE 6 is a top plan view thereof;

FIGURE 7 is a bottom view which is also substantially the same as such view of the FIGURE 1 embodiment;

FIGURE 8 is a side elevation of another modified form of the FIGURE 1 embodiment of my invention;

FIGURE 9 is a top plan view thereof;

FIGURE 10 is a bottom view; and

FIGURE 11 is one end elevation and is substantially the same as the other end elevation thereof.

The broken lines showing a removable key are for illustrative purposes only.

I claim:

The ornamental design for a keyholder, as shown and described.
